(57) **CLAIM**

The ornamental design for a visor as shown and described.

DESCRIPTION

FIG. 1 is a perspective view of a designer visor;

FIG. 2 is a front plan view thereof;

FIG. 3 is a rear plan view thereof;

FIG. 4 is a top plan view thereof;

FIG. 5 is a bottom plan view thereof;

FIG. 6 is a left side plan view thereof; and,

FIG. 7 is a right side plan view thereof.

The evenly dashed broken lines along the surfaces of the visor depict stitching that form part of the claimed design.

1 Claim, 6 Drawing Sheets
